RENÉ JEAN PAUL EMILE COZETTE, OF NEUILLY-SUR-SEINE, FRANCE.

ROTARY PUMP AND COMPRESSOR.

Application filed June 15, 1926. Serial No. 116,225.

This invention relates to high speed rotary pumps and compressors.

Among the objects of the invention are, to simplify the construction of devices of this character; to cheapen the cost of their production, and to increase their efficiency and life.

Further objects and advantages will appear in the following description of the invention.

In the accompanying drawings is represented in a schematic manner, and by way of example only, two ways in which this invention can be carried out.

15 In the drawings:

Fig. 1 is a transverse sectional view of a usual construction of pump of the kind in question.

20 Fig. 2 is a transverse sectional view on line 2—2 of Fig. 3.

Fig. 3 is a longitudinal sectional view on line 3—3 of Fig. 2.

25 Fig. 4 is a sectional view on line 4—4 of Fig. 3, showing details of the drive means employed.

Fig. 5 is a view similar to that of Fig. 3, but showing a second form of drive means.

30 Fig. 6 is a sectional view on line 6—6 of Fig. 5, showing details of a second form of drive means.

In order that the advantages of applicant's construction can be readily realized a short description of the usual form of this type of device follows:

35 Pumps of this character are usually constituted (see Fig. 1) by a cylindrical body or stator S, within which rotates a cylindrical drum or rotor R, the axis of the rotor is parallel to that of the stator but is positioned eccentric thereto by an amount h whereby the rotor contacts with the inner surface of the stator, at the point A. A plurality of blades P is positioned in slots r formed in the rotor.

40 A device constructed as described just above operates in the following manner. If it be assumed that the rotor moves in the direction of the arrow f, it will be seen that passing from the point of tangency A, the volume of the compartment included between two consecutive blades increases constantly throughout a travel of 180° . This volume becomes a maximum when the com-

partment under consideration reaches the point B. The compartments which are thus at the inlet condition communicate with the inlet conduit C.

On the contrary, during the second half revolution the volume of each compartment constantly decreases until it becomes a minimum once more at the point of tangency A. These decreased sized compartments communicate with an outlet conduit D and thus fluid is forced out through the conduit D.

45 In such an apparatus the displacement of the blades P in an outward direction and the application thereof against the inner surface of the stator S, is produced by the action of centrifugal force which comes into play due to the rotation of the rotor.

50 These devices are very simple in construction and thus from this point of view are very desirable, but at the same time they have two principal defects as set forth in the following:

55 In the first place the displacement of the blades in an outward direction is produced by the action of centrifugal force and hence such displacement does not take place until after a certain speed of rotation is attained. Below this speed the blades do not afford a tight contact with the inner surface of the stator and thus the pump does not function at these lower speeds.

60 A second defect in such devices is due to the fact that the pressure of the blades on the inner surface of the stator, which is due to the action of centrifugal force, increases according to the square of the speed of rotation and thus rapidly reaches a very high value. As a result considerable friction is created between the blades and the stator and this very materially decreases the output of the device and hence lowers its efficiency. Under such conditions the pressure between the blades and the stator is ideal for highest efficiency only at one particular speed.

65 A further defect arises in that in beyond a certain speed lubricant is expelled due to the rotation, and hence with insufficient lubrication the blades and the stator wear very rapidly.

70 The device constructed in accordance with the invention, however, and a detailed description of which is given below wholly

overcomes the above set forth defects. In order to clearly show the advantages of the new construction the above description of the usual form of construction is quite essential.

6 A device according to the present invention comprises a rotor 1, the axis of which is parallel to the axis of a stator 2 but which is eccentric thereto so as to be tangent to the 10 stator along a stator generatrix at 3. The rotor is formed of a plurality of like sectors 4, each connected by screws or the like 5 at each end, to plates 7, which plates carry hollow cylindrical axles 8 of large diameter, 15 mounted on roller bearings 9 so as to rotatably support the rotor.

Each sector 4 of the rotor is spaced from the adjacent sector by a distance permitting a blade 10 to slide therebetween. Each of 20 these blades 10, which are the propelling blades of the pump, is pivotally carried by a suitable system of pivoting means, to a tubular shaft 11 the axis of which coincides with the general axis MN of the stator.

25 The blades are formed from rectangular sheets of steel or other suitable material and are each attached at three points, as shown in Fig. 3, to three sleeves 12 which are carried by, and can readily turn with but slight friction 30 on the axle 11. The blades are fastened by means of rivets, for example, between the arms 15 carried by the sleeves 12 (Figs. 2 and 3).

The shaft 11 passes through the hollow 35 cylindrical axles 8 of the rotor and is supported on ball bearings 16.

With the above described construction the blades 10 consequently turn about the general axis MN of the stator, and being carried 40 by the axle 11 they cannot separate therefrom due to centrifugal force. Thus the bearing of the blades against the stator can be adjusted to the proper amount and does not depend on, or vary during, the operation 45 of the device.

It will, therefore, be possible to adjust the outer edge of the blades relative to the stator so that there will be no leakage therebetween without fear of causing undue friction 50 which would result in harm to the blades and to the stator.

It is to be noted that as a result of centrifugal force the blades press their sleeves 12 against the axle 11 and thus carry the 55 axle 11 around with them in their rotation so that but little wear is caused between the axle 11 and the sleeves 12.

There is, however, a slight relative motion 60 necessary between the axle 11 and the sleeves, due to the eccentric mounting of the rotor relative to the stator, as can be seen from the angular variation between the blades and the rotor (Fig. 2). This relative motion between the axle and the sleeves 14, is during each half revolution deter-

mined by the angle 17, Fig. 2, which due to the small diameter of the axle 11 is of little relative importance.

It is very evident that the arrangement of these various details of construction could 70 be considerably modified without thereby changing the principle of the invention. In particular it would be possible to have a tubing rotatably carrying the blades and journaled on the shaft fixed on the case. 75

As already noted above, as a result of the eccentricity of mounting, although the sectors constituting the rotor are equal to each other, the angles which the blades make with the sector through the rotation, are not 80 equal. This angle is a maximum when the blade under consideration is at the point B, Fig. 1, that is at the end of admission. On the other hand this angle is a minimum when such blade reaches the point of A 85 which is the end of the exhaust position. This condition of change of angularity of the blades with respect to the rotor segment, producing an increased out flow volume and increases the pressure which the device is 90 capable of giving.

A difficulty is now encountered in rotating the rotor at an angular speed equal at all times to the drive axle.

It would be possible to rotate the rotor 95 by means of the axle 11 which carries the blades, by making use, for example, of a drive blade which would be fixed to the axle 11, but in this case the rotation would not be regular. In such a case the angular speed 100 of rotation would be a maximum at A and a minimum at B.

This would have the effect of causing inertia effects and vibrations which are always prejudicial to the operation of such 105 devices. Also the driving blade which would have to do a very considerable amount of work would rapidly become worn out.

It is, therefore, preferable to directly drive the rotor so that the rotor can then 110 cause the angular displacement of the blades. This displacement of the blades relative to the rotor is very small, the angle 17, and since the blades are very light and are supported by the axle 11 the inertia effects set up will be quite negligible and no harmful vibration produced.

The actual structural arrangement adapted is the following. One of the axles 8 Fig. 3 is furnished with a gear 18 which meshes with a drive gear 19 fixed to the drive shaft 20.

The above described drive is a particularly desirable form as the gear 18 is driven by an outer gear 19 fixed to the drive shaft 20 which is positioned in the general axis MN of the device. In this case the ball bearing 16 supporting the shaft 11 can be placed at the interior of the shaft 20 as shown in Fig. 3. The shaft 20 is in turn supported

by two ball bearings 21. It is to be noted that since the gear 19 is of greater diameter than the gear 18 of the rotor, the latter will turn faster than the former and this will 5 readily permit of reducing the dimensions of the pump or compressor.

Fig. 5 shows a second form of drive wherein the drive shaft is parallel to the general axis MN of the device, but where the 10 drive is effected by exterior gears. The gear 18 in this case meshes with a gear 22 fixed to a drive shaft 23 which is supported by two ball bearings 24. The axle 11 in this case is supported by two ball bearings 25 15 which rest directly in the casing of the pump.

Having described my invention, I now claim:

A rotary pump, comprising, a stator with 20 an inlet and an outlet, a rotor positioned

within, and eccentric to, the stator, propeller blades rotatably carried by the rotor and non-movable thereto in a radial direction, a gear at one end of the rotor, a drive shaft, coaxial with the stator, and a gear on the 25 drive shaft in mesh with the rotor gear, the drive shaft in a fluid tight manner 30 against the inner surface of the stator, an axle journaled at each end in, and concentric with, the stator, separate collars snugly but rotatably carried by the axle, the blades being each fixed to separate ones of the collars.

In testimony whereof I have signed my name to this specification.

RENÉ JEAN PAUL EMILE COZETTE.
